SISSAK K. OUZOUN-BOGHOSIAN, OF WASHINGTON, DISTRICT OF COLUMBIA.

DESIGN FOR A CLOCK-CASE.

• 57,373.

Specification for Design.

Patented Mar. 15, 1921.

Application filed April 13, 1920. Serial No. 373,566. Term of patent 3½ years.

To all whom it may concern:

Be it known that I, SISSAK K. OUZOUN-BOGHOSIAN, a subject of the Sultan of Turkey, having declared my intention of becoming a citizen of the United States, residing at the city of Washington, District of Columbia, have invented a new, original, and ornamental Design for a Clock-Case, of which the following is a specification, refer-

ence being had to the accompanying drawing, forming part hereof.

The figure is a perspective view of a clock case, showing my new design.

I claim:

The ornamental design for a clock case, as shown.

In testimony whereof I affix my signature.

SISSAK K. OUZOUN-BOGHOSIAN.
